BUTTER PAT PACKAGING
Leo Peters, 750 Plymouth Road SE,
Grand Rapids, Mich. 49506
Filed Sept. 1, 1966, Ser. No. 576,687
12 Claims. (Cl. 99—179)

This application is a continuation-in-part of my co-pending application, Ser. No. 329,000, filed Dec. 9, 1963, now abandoned.

This invention relates to the packaging of butter pats of the individual-service size normally served in restaurants. Such pats are usually about $1\frac{1}{4}$ " square by $\frac{1}{4}$ " thick and are served to individual diners for a single meal. In particular, this invention relates to a method and means of packaging decorative-surfaced pats of butter on their own individual service plates so as to (1) protect the decorated surfaces from surface-marring contacts during transportation through the channels of trade, and (2) have the pats quickly and easily available for immediate service at the point of end use on a dining table.

More especially, this invention relates to a paper plate with extending hinged side flanges, and a surface-decorated butter pat that rests with its nondecorative surface on the plate. The side flanges of said plate are upright and erect during transportation so as to provide (1) an encircling, perimetric shield, and (2) upright supports to protect the pat against the weight and pressure from above and below within the shipping case, and (3) readily-operable gates through having the side flanges movable outward and downward so as to make the butter pat readily accessible to a diner at point of end use.

A brief review of the prior art within the butter-patty industry, as it bears on the adaptability (and/or lack of it) to the packaging of decorative-surfaced pats, is germane to an understanding of the reasons for this invention.

Within the segment of the butter industry that caters to the restaurant trade, butter patties for table service are manufactured and packaged in two principal ways: (1) A scored slab of butter that requires breaking along the score lines in order to separate and serve individual patties; and (2) Individual patties placed on paper plates ready for immediate serving in a restaurant.

It is this second method which is the concern of this invention, namely, the packaging of butter patties on individual serving plates.

In order to carry this second method safely through the channels of trade, it has been the practice of the prior art (a) to place a butter patty on a paper plate that is about one and one-half times larger than the square inch area of the patty so that said plate provides at least a $\frac{1}{4}$ " perimeter extending out from the sides of said patty, then (b) to place a parchment paper liner or cover on top of said patty to function as a divider between the top of a patty and an adjacent patty plate. Thereafter, the plate-supported patty (c) is packed in contacting relationship to its neighbors in a shipping case, and (d) all patties thus packaged are stacked in order that no accumulated stacked weight will rest on any individual patty during storage or transportation.

It is the deficiencies of this second (i.e., paper-plated patty) method of the prior art that is of concern here. This prior art method of butter-patty packaging has certain features that are considered undesirable by many restaurants, an undesirableness apart from any consideration of decorative surfaces. For the decorated patty which is involved in this invention, the undesirableness of the prior art is of such direct importance that the prior art methods are outright harmful and commercially impractical. The deficiencies of the prior art for decorative

2

patties are especially harmful in the following two respects:

(1) Parchment paper liners on top of each patty. When these liners are peeled off, part of the butter patty frequently comes off with them, and this is always true when the butter is warm. The result is that the patty is left looking messy; any surface decorations that are on the patty are ruined; and the diner is required to scrape butter from both the liner and the paper plate. It is obvious that the embossed surface decorations on patties, such as those which are the subject of this invention, would be completely destroyed by this kind of packaging.

(2) The edge-stacking arrangement of the prior art (a) requires the patties to be pressed close together in order to prevent slippage of the pat from its plate while in transit—this pressure has a tendency to thin out the patty and at the same time obliterate any design that may have been imprinted on its surface, and (b) requires a packaging arrangement that takes one and one-half times more space than would be needed if the patties could be packed in closer relationship. Such a shipping-stacking arrangement, with its constant pressures on the surfaces of the butter, is, at best, damaging to engraved (imprinted) surface designs of the kind that have been used on butter pats heretofore. For surface designs that are embossed (upraised) such as those which are new and used with this invention, such a shipping-stacking arrangement is fatal, rendering its use commercially impossible.

Part of the purpose, then, of this invention is to overcome the disadvantages and deficiencies in the prior art of packaging butter patties on individual-size plates; at least insofar as such packaging influences the retention and/or destruction of surface decorations on the patties. More importantly, it is the purpose of this invention to provide a commercially practical method for packaging decorative-surfaced butter pats on individual-size serving plates.

It is interesting to note that in the pursuit of the purposes of this invention three (3) new, interdependent, cooperating, commercially advantageous and rather surprising results are achieved. These are:

(1) The stacking of layers of decorative-surfaced butter patties on top of each other in a highly compact arrangement; yet, surprisingly, without having anything touching the decorative surfaces.

(2) Positive four-sided, pressurized and equalized, contact between the sides of adjacently-positioned patty plates in a combination grouping, whereby they push against, yet support and cooperate with, each other to maintain each side of said patty plate vertically erect; yet, surprisingly, doing this without exerting any pressure inwardly on the butter which, if it happened, would cause damage; or, outwardly against another plate which, if it happened, would cause said plate to pop out of its cooperating position within said group and destroy the ability of the group to protect its butter pats.

(3) A dual, self-reversing, self-contradictory role played by the paper plate whereby (a) while in transit it functions as an all-enveloping, completely protective butter patty container, with its hinged sides in rigid upright position serving as weight-supporting columns, and then, surprisingly, (b) upon removal from its shipping case, the plate automatically drops its protective role by dropping its hinged sides and exposing the top and sides of the butter so the patty is completely accessible to a diner's knife.

Here is patty packaging that is highly protective, with its butter completely non-accessible while moving in shipment through the channels of trade, and then, surprisingly, becomes completely non-protective, with its butter highly accessible, when it reaches the end of its journey and is served on a dining table.

3

By way of summing up the contradictory nature of this surprising invention, it can be put this way: The subject of this invention has a protecting package structure at the beginning of its life, and then automatically, upon release from its shipping-case confinement, changes its structure to that of a serving plate at the end of its life. Or, summing up another way: while in transit through the channels of trade, the structure of this invention functions as a highly cooperative and important member of a large number of butter-patty plates, and then in end use it changes its structure to function as a highly independent, individualized, butter-serving plate.

The apparent simplicity with which this invention has achieved the preceding surprising, reversible, contradictory results is surprising in itself. This has been achieved with the following simple paper plate structure:

(1) A blank of paperboard of the same base shape as a butter patty, but having linear dimensions slightly larger than the base of the pat plus an amount slightly in excess of the thickness of the pat;

(2) The blank being scored, creased or perforated along the four outside edge lines at which a centered pat rests on the blank, and the corners to the outside of the lines being scored or cut out so that the blank has four manipulatable flanges, extending beyond the periphery of a centered butter pat, which, in effect, are hinged to the main section of the blank along the scored lines;

(3) Preliminary flexing of these peripheral extensions, or hinged flanges, along the score lines to reduce the bending resistance of the paperboard in an amount that will permit said flanges to stand erect in cooperation with and under equal pressure from adjacent patty plates;

(4) Raising the hinged flanges along the score lines so that they stand erect, in which position they are slightly higher than the thickness of the accompanying butter pat;

(5) Packing numerous patty plates together on a common sheet so that the plates cooperate with each other to maintain their hinged sides erect, in which position the sheet will serve as a base for one grouped layer of patty plates and as a non-touching cover for butter patties of a grouped layer immediately below whose erect hinged flanges support the sheet on which the upper group rests.

In the immediately preceding description of my butter-patty plates in packed position, the following commercially advantageous results are achieved:

(1) There is no top surface contact with or pressure on any butter patty. Thus, any kind of surface decoration can be employed without danger of damage or obliteration. In addition, even an undecorated butter pat, due to this lack of pressure on the butter, is maintained with its original shape and thickness inviolate; there is no flattening, thinning, or spreading-out caused by package pressures.

(2) Because there is no pressure on the butter patty, no top liner in contact with the butter is needed to keep the butter from sticking to the adjacent plate or patty, and thus no loss of butter or decoration is possible due to the stripping off of a liner.

(3) Practically no more storage or shipping space is required than if the patty was not paper-plated.

(4) The compactness in shipment does not interfere with ease of use on the dining table because the upright extensions of the plate fall down when the plate is removed from the shipping case.

In summary, the deficiencies of the prior art are eliminated and a new packaging structure achieved by this invention; a packaging structure which makes commercially practical the transportation and sale of decorative-surfaced butter patties packaged on individually paper plates, and improves the commercial acceptability of non-decorative butter patties.

It is an object of this invention to provide a commercially practical method and means for both shipping and serving patties on individual patty plates, and, in particular, decorative-surfaced butter patties.

It is another object of this invention to provide a butter-patty plate which eliminates the need for a cover which is in contact with the butter.

It is still another object of this invention to provide a method and means for shipping and serving individually plated, decorative-surfaced, butter patties by which the decorated surfaces are not required to touch any package surfaces.

Yet another object of this invention is to provide a paper plate for a butter patty which provides a method and means for packaging and shipping the butter patty that eliminates all weighted and/or pressured contact between the butter patty and its package except the contact between the bottom of said patty, where it rests on the plate, and the plate.

A further object is to use the side extensions of grouped patty plates as the upright column supports for all butter patty packaged weights carried in a large shipping container.

A yet further object is to use the hinged side flanges of butter-patty plates for column supports which cooperate with and support each other in maintaining erect supporting columned positions in groupings of plated butter patties.

A still further object is to use virtually no more packing space for a plated butter patty than would be required for an identical butter patty without a plate.

Another object is to provide a butter-patty plate which will make the butter patty easily and immediately accessible to a diner without the need for removing any part of the patty-packaging components.

An overall object is to provide a butter-patty plate which will function as a compact, space-conserving, enveloping protector for a decorative-surfaced butter patty during storage and transportation; and then, at point of end use by a diner, reverse its protective role and, without requiring any special manipulation by the diner, have the butter patty openly and easily accessible for the diner's use.

The invention is explained in conjunction with an illustrative embodiment in the accompanying drawing, in which:

FIG. 1 is a perspective elevational view of a shipping case, one of the supporting trays partially removed to illustrate generally the practice of the invention;

FIG. 2 is an enlarged fragmentary sectional view such as would be seen along the sight line 2-2 applied to FIG. 1;

FIG. 3 is a plan elevational view of one of the patty-carrying plates prior to use in the invention;

FIG. 4 is a perspective elevational view showing one patty-carrying plate positioned on a tray so as to delineate the relationship of the various elements of the invention;

FIG. 5 is a perspective elevational view of a plate with the butter patty mounted thereon;

FIG. 6 is a view similar to FIG. 5 but showing the patty-carrying plate in a subsequent stage of packaging;

FIG. 7 is a view similar to FIG. 6 but featuring cooperative patty-carrying plates arranged in juxtaposition thereto and in dotted line to aid in the understanding of the cooperative relation utilized in the practice of the invention;

FIG. 8 is a perspective elevational view of a patty-equipped tray in the condition it assumes at the time of use; and

FIG. 9 is a fragmentary perspective elevational view of a patty-equipped tray featuring triangular-shaped patties.

In the illustration given, and with particular reference to FIG. 1, the numeral 10 designates generally an outer case or carton employed for transshipping a plurality of butter patties of the character seen in FIG. 5 wherein the patty is designated by the numeral 11. Each patty 11 is supported on a plate generally designated 12, and the patty 11 is embossed as at 13, i.e., equipped with upstanding decoration. In the particular illustration given, this takes the form of a star with certain fluting disposed on the top

surface 14 of the patty 11. The patty 11, in accordance with conventional practice, is square, i.e., generally rectangular, and normally measures about one inch on each side, upstanding about $\frac{1}{4}$ ".

It will be seen from reference to FIG. 1 that a plurality of the plates 12 are supported on a tray generally designated 15, and that the case 10 accommodates a plurality of these trays 15.

An advantageous arrangement of plates 12 within a given tray 15 is seen in FIG. 4, wherein 40 spaces are outlined in broken line for the accommodation of the plates.

Each plate at the outset assumes the planar configuration seen in FIG. 3, wherein the tray is equipped with a generally rectangular (in the illustration given, square) support portion 16 defined by lines of weakness along the four sides as at 17, 18, 19 and 20. Integral with the support portion 16 and partially defined by the above-mentioned lines of weakness 17-20 are four flange portions as at 21, 22, 23 and 24. Advantageously, the lines of weakness 17-20 may be developed by scoring or perforating as shown, to permit the flange portions 21-24 to be moved upwardly into generally erect positions as at 20 in FIG. 6. This defines a five-sided cell for protecting the patty 11, notably all four sides and the bottom. The fact that the sides as at 25 in FIG. 5 are protected can be seen from the fact that the butter patty 11 is spaced inwardly of the line of weakness 20 associated with the flange portion 24 to define a perimetric space as at 26. This spacing 26 is provided relative to all four sides of the butter patty 11.

In the practice of the invention, the flange portions 21-24 are initially provided coplanar with the support portion 16, as indicated in FIG. 3. This is performed, in one aspect, by employing steel dies for simultaneously scoring and cutting 8 to 10 point paperboard (0.008-0.10" thick). Thereafter, the flange portions 21-24 are "overfolded" by being pivoted through a vertical arc (when the support portion 16 is disposed horizontally), with the lines of weakness 17-20 serving as hinges. The vertical arc is slightly in excess of 90° , i.e., of the order to $100-120^\circ$, so as to eliminate a substantial portion of the resistance or "fight" inherent in the hinge connection between the various flange portions 21-24 and the support portion 16. However, a certain inherent resiliency remains which in time tends to return the flange portions 21-24 toward a coplanar relationship with the support portion 16. As seen in FIG. 6, the flange portions have unfolded partway toward the coplanar relationship with the support portions.

In this condition (as seen in FIG. 6), a plurality of the plates 12 are disposed on the trays 15, as illustrated in FIG. 2. Each tray 15, as seen in FIG. 4, also has a base or support part as at 27 and upstanding perimetric flange parts 28, 29, 30 and 31, each of which is analogously developed through lines of weakness.

The cooperative relationship between juxtaposed or adjacent plates can be most readily appreciated from a consideration of FIG. 7 wherein the solid line plate is again designated by the numeral 12 and is seen to be flanked or confined by other trays generally designated 12a, 12b, 12c and 12d. Each tray 12a-12d has its associated flange portions tending to return toward a coplanar relation with the base or support portion thereof and thus when brought into mutual engagement with adjacent plate flange portions, serve to mutually support and immobilize the plate in place, as can be appreciated from the contact designated 32 in FIG. 2. The showing in FIG. 2 is exaggerated, since in this condition the flange portions as at 21 which define the bearing 32 are vertically erect, i.e., approaching 90° relative to the base or support portions 16.

In like fashion, the flange parts 27-31 associated with each tray 15 are likewise disposed substantially erect relative to the horizontally disposed base part 27. The confinement of the upstanding parts 28-31 is achieved through the cooperation of the various flange portions of the supported plates 12 and the interior of the walls 10a, etc., of

the exterior case 10. The case 10 is seen to be advantageously constructed of corrugated paperboard as at 33, wherein the end flaps 34 and 35 of the case 10 are seen in open condition. It is preferred to provide definite access to the ends of the case 10 (the smaller area sides) so as to facilitate tray removal as indicated in FIGS. 1 and 2 wherein a tray 15 is seen being removed generally horizontally and in which case there is a slight lessening of the bearing pressure between adjacent plates 12 as evidenced by the fact that the most adjacent trays as at 12e in FIG. 2 have moved slightly to the left, developing a lesser bend in the flange part 31.

Still referring to FIG. 2, it will be seen that the cooperation of adjacent trays and the plurality of plates confined and supported thereon develop a plurality of cellular units such as is designated 36 in FIG. 2, wherein the flange portions 21-24 provide sides of the cellular unit, the support portion 16 provides the bottom, and the undersurface of the tray 15 as at 27a defines the top of the cellular unit, which has a height slightly in excess of the height of the patty 11. In other words, the flange portions 21-24 have a width dimension, i.e., the dimension perpendicular to the associated line of weakness, slightly in excess of the height of the patty 11 confined thereby.

25 Inasmuch as the uppermost tray 15 (the one partially removed in FIGS. 1 and 2) has no cooperating tray above it to develop the cell 36, a cover sheet of similar makeup to the plate is provided as at 37. In the operation of the invention, a plurality of plates 12 and trays 15 are provided for each case 10. The plates 12 are overfolded along the lines of weakness 17-20 to partially defeat the inherent resiliency along these lines, so that the flange portions 21-24 will normally assume the position relative to the support portion seen in FIG. 6. Thereafter, a plurality of plates 12 (forty, in the illustration given) are assembled on each tray 15, with the adjacent abutting flange portions of the various plates cooperating to urge each other into a general condition such as is illustrated in FIG. 7. In the illustration given, fifteen such trays are packed within the outer case 10, with the upper tray being equipped with a cover sheet as at 37. In this instance, the outer walls of the case, more particularly, the interior surfaces of the outer walls 10a, serve to confine and urge toward vertical position the various flange parts 28-31 of the vertically-arranged trays 15.

When the case 10 is complete, the case is suitably closed with indicia provided thereon indicating that the case should be opened from one of the smaller ends to provide the configuration seen in FIG. 1. The case may be transshipped under refrigeration to a site of ultimate use, hotel, restaurant, or the like. When the case 10 is opened and a tray removed, it is seen that the inherent resiliency of the flange portions 17-20 again develop the configuration of FIG. 6 and in particular when a tray 15 is partially removed, as in FIGS. 1 and 2, the confronting flange portion as at 21a extends away from the vertical more than the other flange portion, this being illustrated in FIG. 8, wherein the projecting flange portion 21a serves as a convenient finger tab for holding plate 12 conveniently in a position for a diner to "knife-off" portions of the patty 11 for consumption. Notwithstanding the substantial depression of the flange portion 21a, the remaining flange portions 22a, 23a and 24a in FIG. 8 remain in a partially-erect position so as to stabilize the support portion 16a against flexure and possible loss or slippage of the patty 11. When the plate 12 of FIG. 8 is positioned on a serving table, or the like, the flange portion is not depressed as in 21a and the various flange portions will maintain substantially the configuration seen in FIG. 6 where there is ample knife access portion to the patty 11 for removing an increment of the butter patty for spreading bread, rolls, etc.

Excellent results have been obtained through providing butter-patty packaging of the character illustrated. The advantageous use of space makes it possible to ship

a substantial weight of butter in a small volume—the interior volume of the case being used most efficiently, as can be appreciated from a consideration of FIG. 2, wherein the only unused interior space is provided as a protective perimeter for the patties 11. It will be appreciated that in FIG. 2 the adjacent flange portions 21-24 have relaxed partially from their erect condition assumed during transport, since one end of the case 10 has been opened. When the case is sealed, the various flange portions 21-24 are almost vertical, i.e., perpendicularly oriented relative to the associated support portion 16.

Through the use of an essentially rigid, yet flexible, construction of the plates 12, the upstanding edges as at 38 of the various plates 12 develop a positive bearing support for the trays 15 carried thereby.

In FIG. 9, it is seen that the arrangement of FIG. 4 is presented except that the patties are triangular in shape, and hence the supporting plates are likewise triangular, i.e., right triangles, so as to utilize the benefits of the invention, yet render it suitable for use in connection with marketing oleomargarine—see Public Law 459, Section 409(c) (2).

While in the foregoing specification a detailed description of an embodiment of the invention has been set down for the purpose of illustration, many variations in the details herein given may be made by those skilled in the art without departing from the spirit and scope of the invention.

I claim:

1. A butter-pat package, comprising: a plurality of pat-carrying plates, each equipped with a central support portion of generally rectangular outline, an integral flat flange upstanding from each side of said rectangular outline, an embossed-top butter pat positioned on said support portion a spaced distance away from each flange, with the flanges projecting upwardly above the pat, and a confining case urging the flanges of the plate into cooperative bearing relation with the flanges of adjacent plates, said case also supporting the support portions of said plates in generally coplanar relation, said flat flanges being constructed of resilient material whereby said flanges tend to pivot outwardly when the aforesaid cooperative bearing relation ceases.

2. The structure of claim 1 in which said package includes a plurality of generally rectangular trays, each equipped with integral perimetric flanges, each of said trays supporting a plurality of plates within said case in vertically-stacked relation whereby each tray serves a dual function as a base for one group of plates and as a top for an adjacent group.

3. A butter-pat package comprising: an outer case having the exterior configuration of a rectangular solid and defining thereby a pair of end walls of smaller area than the other walls of the case, means releasably closing at least one of said end walls, a plurality of trays arranged in vertically-stacked relation in said case removable through said one end wall when said one end wall is disposed vertically, each tray including a generally planar, rectangular support part disposed horizontally and four upstanding flat-flange parts integral with said support part, each of said flange parts being defined by a line of weakness in the tray associated therewith to provide said flange part with resilience tending to pivot said flange part toward coplanar relation with said support part, a plurality of generally square plates supported on each tray, each plate including a generally planar, square support portion disposed horizontally and four upstanding flange portions integral with said support portion, each of said flange portions being defined by a line of weakness in the plate associated therewith to provide said flange portion with resilience tending to pivot said flange portion toward coplanar relation with said support portion, and an embossed-top butter pat on and within the perimeter of each plate support portion, the flange portions of said plates projecting above said pat to define with a

tray above a protective cell for the top surface of said pat and with the flange portions and parts cooperating with the walls of said case to immobilize said trays and plates.

4. A butter-pat package, comprising an exterior case, a plurality of trays vertically arranged within said case, a plurality of plates on each tray horizontally arranged relative to each other, and an embossed-top butter pat on each plate, each plate including a blank of paperboard conforming in general to the base shape of said butter pat, but dimensioned slightly larger than the base of the pat plus an amount slightly in excess of the thickness of the pat, said blank being weakened along four outside edge lines to develop four manipulatable flat-flange portions extending beyond the periphery of the butter pat centered on the blank, said flange portions being flexible to stand erect in cooperation and under equal pressure from flange portions of adjacent plates, whereby the said plates cooperate with each other to maintain the generally-erect flange portions erect in which the said tray serves as a base for one grouped layer of butter-pat plates and as a non-touching cover for butter-pat plates of a grouped layer immediately below whose erect flange portions support the tray on which the upper group rests, thereby completing a protective shipping confinement for said butter pat and whereby said flanges will hinge outwardly and downwardly when said plates are removed from said exterior case and in so doing will release said butter pat from said protective confinement and expose it to easy access.

5. A butter-pat package, comprising a plurality of pat-carrying plates each equipped with a central support portion of generally rectangular outline and an upstanding flat integral flange connected to each side of the rectangular outline, with the flanges projecting upwardly above the pat centered on said support portion, a butter pat positioned on said support portion a spaced distance away from each flange, said plate being constructed of fibrous material whereby said flange portions are manipulatable to a generally perpendicular position relative to said support portions but possessing sufficient inherent resiliency to tend toward return to pivot outwardly from said pat, said flanges being dimensioned when in generally erect position to project above the top surface of the pat, said pat having an embossed-top surface, and a confining case urging the flanges on one plate into cooperative bearing relation with the flanges of adjacent plates to define an essentially rigid cellular construction for shipment, yet which develops a readily-accessible serving when a plate is removed from said case.

6. In a method of butter-pat packaging, the steps of: forming a plurality of pat-supporting plates, each plate having a generally square support portion and four flat integral flange portions, folding said flange portions through an arc of more than 90° to define an open-topped cell wherein the flange portions possess sufficient resilience to tend toward coplanar relation with said support portion, positioning an embossed-top butter pat on each support portion a spaced distance away from each flange portion associated with said support portion, and assembling a plurality of said plates within a confining case in mutual flange portion contacting relation whereby the resiliency of said flange portions causes them to cooperate among themselves and with said case to develop bearings immobilizing each plate within said case.

7. The method of claim 6 in which said forming step is performed by cutting paperboard blanks.

8. The method of claim 7 in which said cutting step includes simultaneous scoring of said blanks to provide lines of weakness defining said flange portions.

9. The method of claim 7 in which said plates are subsequently removed from said confining case, whereby the resiliency of said flange portions causes them to move outwardly and downwardly so as to expose said butter pat for easy access.

10. In a method of butter-pat packaging, the steps of die-cutting a paperboard blank to provide a plate having a generally square planar support portion and four perimetric flat-flange portions integral with said plate portion, and overfolding said flange portions through an arc of slightly in excess of 90° above the plane of said support portion, thereafter placing an embossed-top butter pat in each plate and arranging a plurality of said plates with the flanges thereof in cooperative bearing relation, said flanges tending to pivot outwardly when the aforesaid cooperative bearing relation ceases.

11. A butter-pat package, comprising: a plurality of pat-carrying plates, each equipped with a central support portion, an integral flat flange upstanding from each side of said support portion, an embossed-top butter pat positioned on said support portion a spaced distance away from each flange, with the flanges projecting upwardly above the pat, and a confining case urging the flanges of one plate into cooperative bearing relation with the flanges of adjacent plates, said case also supporting the support portions of said plates in generally coplanar relation, said flat flanges being constructed of resilient material whereby said flanges tend to pivot outwardly when the aforesaid cooperative bearing relation ceases.

12. A butter-pat package, comprising an exterior case, a plurality of trays vertically arranged within said case, a plurality of plates on each tray horizontally arranged relative to each other, and an embossed-top butter pat on each plate, each plate including a blank of paperboard conforming in general to the base shape of said butter pat, but dimensioned slightly larger than the base of the pat plus an amount slightly in excess of the thickness of the pat, said blank being weakened along the outside edge

5 10

15

lines to develop manipulatable flat-flange portions extending beyond the periphery of the butter pat centered on the blank, said flange portions being flexible to stand erect in cooperation and under equal pressure from flange portions of adjacent plates, whereby the said plates cooperate with each other to maintain the generally erect flange portions erect in which the said tray serves as a base for one grouped layer of butter-pat plates and as a non-touching cover for butter-pat plates of a grouped layer immediately below whose erect flange portions support the tray on which the upper group rests, thereby completing a protective shipping confinement for said butter pat and whereby said flanges will hinge outwardly and downwardly when said plates are removed from said exterior case and in so doing will release said butter pat from said protective confinement and expose it to easy access.
